UNITED STATES PATENT OFFICE.

WALTER R. SCHLAGE, OF BERKELEY, CALIFORNIA.

DOOR-LOCK.

1,313,920.

Specification of Letters Patent. Patented Aug. 26, 1919.

Application filed March 29, 1917. Serial No. 158,189.

To all whom it may concern:

Be it known that I, WALTER R. SCHLAGE, a citizen of the United States, residing at Berkeley, in the county of Alameda and State of California, have invented new and useful Improvements in Door-Locks, of which the following is a specification.

This invention relates to a door lock.

One of the objects of the present invention is to provide a simple, substantial, cheaply manufactured, easily applied locking mechanism operated by the door knob whereby the latch in a door lock may be locked against movement when extended. Another object of the invention is to lock the knob, the spindle and the hub against turning movement and the latch against depression by a jimmy and also to provide means for visibly indicating whether or not the door is locked. Further objects will hereinafter appear.

The invention consists of the parts and the construction and combination of parts hereinafter more fully described and claimed, having reference to the accompanying drawings, in which—

Figure 1 is a central, vertical section through the lock, showing the construction of the lock;

Fig. 2 is a cross section on the line 2—2 of Fig. 1;

Fig. 3 is a plan section on the line 3—3 of Fig. 2;

Fig. 4 is a side elevation similar to Fig. 1 showing the application of the invention to a lock of the easy-latch type;

Fig. 5 is a perspective view of the link 25.

Referring to the drawings in detail, A indicates the casing of a mortise door lock, 2 the front plate, 3 the latch, 4 the latch plate, the rear end of which is fork-shaped to straddle the spindle 5 and the hub 6, and which is also provided with a pair of upturned shoulders 7 adapted to be engaged by the hub lugs 8.

9 indicates an ordinary bolt, 10 the bolt bar, which, together with the bolt, is adapted to be retracted or extended by means of an ordinary key inserted through a hole 11; 50 the latch 3 and the bolt 9 being held in their normal positions by means of a coiled spring 12 secured upon the hub 13 formed within the casing. Formed in the casing on the rear side of the hub 6 is a stop 14 over which the latch plate 4 is normally adapted to ride when the spindles and hub are turned

either by the inside or outside knob under normal conditions.

Mounted below the latch plate are a pair of flat springs 15 and 16. These springs 60 are secured at their forward ends by means of screws 17 upon a pad 18 formed within the casing and their upper faces are such that they will form a guide and support for the latch plate, which will permit the 65 latch plate to move back over the stop 14, the upward movement of the springs 15 and 16 being limited by a shoulder lug 19 positioned adjacent or just above the stop 14. In other words, the springs 15 and 16 normally lie on a plane flush with the top surface of the stop 14 and in said position 70 form a guide and support for the latch plate 4.

Rigidly secured in the usual manner on 75 the outside end of the spindle 4 is a door knob 20 and pivotally secured, as at 21, on the inside end of the spindle is a door knob 22. Formed on the inner end of the door knob is a sphere-shaped extension 23 and 80 formed on the inner face of said sphere-shaped projection is a semi-circular notch 24 which is adapted to receive one end of a link 25. This link is in reality interposed between the hub 6 and the sphere-shaped 85 extension 23 on the inner door knob and is held in this position entirely by the notches 26 and 24 and the springs 15 and 16 which, as previously described, exert their pressure on the latch plate 4, which in turn is transmitted through the hub lugs to the hub. 90

The hub is therefore slidably mounted on the spindle and as such permits the knob 22 to be swung about its pivot to assume the dotted line position shown at 22^a. This 95 movement of the knob swings the link 25 into the dotted line position 25^a, and during said movement transmits an endwise movement to the hub upon the spindle which causes it through the lugs 8 to depress the 100 latch plate 4 and springs 15 and 16 to assume the dotted line position indicated at 27 (see Fig. 2). This brings the rear shoulders 7 of the latch plate into the plane of the stop 14, or, in other words, to a position 105 where the latch plate cannot ride over the stop. The latch and plate 4 therefore become locked against endwise movement as the shoulder 7 will engage the front ends 28 of the stop 14. The hub and spindle, together with both of the knobs, are simultaneously locked against turning movement, as 110

the hub lugs 8 cannot swing or turn when the latch plate 4 is locked against movement. The latch 3 is in this manner locked by means of the inside knob 22 and the knobs 5 are in turn locked against turning movement, thus eliminating the necessity of inserting a key and operating the main bolt 9 or lock of the door.

The lock is particularly adapted for bath-
10 rooms, bed-rooms and the like and the pivotally connected knob is, of course, positioned only on the interior side. A person entering a room and desiring to temporarily lock the door will only have to tilt the knob 15 to the dotted line position shown at 22^a. This is not only a quick operation, but it is so easily accomplished that a person will be more liable to lock the door than otherwise.

Another important feature in connection
20 with the device is this: A person may have entered a room, for instance, a bath room, and may have already stepped into the tub and then not be positive whether or not the door is locked. This uncertainty can be
25 obviated by the present lock, as the position of the knob visibly indicates whether or not the door is locked. In other words, the knob serves three functions: first, to retract or ex-
tend the latch; secondly, to lock the latch;
30 and third to visibly indicate whether or not the latch is locked.

The lock attachment as a whole is simple and substantial in construction and can readily be applied to practically any form
35 of lock now in use. While it is here illustrated as attached to a mortise lock, it is obvious that it may be attached to a rim lock or practically any other form of knob-operated lock.

40 A modification of the lock is shown in Fig. 4. This lock is known as the easy-latch, that is, the latch shown in Fig. 1 is normally held in the extended position by means of the spring 12. In Fig. 4 a double
45 latch plate has been provided. The spring 12 will here only engage the lower latch plate, which is retracted or extended by means of the hub knobs, while the upper latch plate, indicated at 30, is slidably
50 mounted independent of the lower latch plate, thus permitting the latch to be held in its extended position by means of a weaker spring 31. The two latch plates are in this instance supported on a plane with relation
55 to the stop 14 by means of springs 15 and 16 in a manner similar to that previously described and are depressed to engage the stop 14 by means of the pivotal mounting of the knob and the interposed link 25. The link
60 employed in both instances is channel-shaped in cross section, as shown in Fig. 5, to permit it to straddle the spindle, which in almost every instance is square in cross section.

65 I, however, wish it understood that vari-

ous modifications of this structure may be employed without departing from the spirit of the present invention within the scope of the claims, and that the materials and finish of the several parts may be such as experience and judgment of the manufacturer may dictate.

70 By referring to Figs. 2 and 3, it will be seen that a collar 60 is provided. This collar is securely fastened by a set-screw, pin, 75 or other means on the spindle 5 and its function is to form a seat against the lock housing A when the knob 22 is thrown up against the pressure of the springs 15 and 16. This collar also renders the locking 80 mechanism independent of the outside knob 20; that is, the spindle cannot be removed or the locking mechanism disturbed even though the outside knob 20 is removed.

85 Having thus particularly described my invention, what I claim and desire to secure by Letters Patent is:

1. The combination with the latch in a lock and the spindle whereby it is actuated of a knob pivotally mounted on the spindle 90 and means operated by swinging movement of the knob about its pivot for locking the latch against movement.

2. The combination with the latch in a lock and the knob whereby it is retracted of 95 means actuated by the knob for locking the latch against retraction in any manner, and means for visibly indicating whether the latch is locked or unlocked.

3. The combination with the latch in a 100 lock and the knob whereby it is retracted of means actuated by the knob for locking the latch against retraction in any manner, and means for determining by the position of the knob whether the latch is locked or unlocked.

4. The combination with the latch and the latch plate in a door lock of a casing inclosing the same, a stop member formed in the casing over which the latch plate is normally adapted to ride, and means for depressing the latch plate to bring it into engagement with the stop. 110

5. The combination with the latch and the latch plate in a door lock of a casing inclosing the same, a stop member formed in the 115 casing over which the latch plate is normally adapted to ride, a yieldable member adapted to normally support the latch plate in said position, and means for depressing the latch plate and the yieldable supporting member to bring the latch plate into engagement with the stop and to lock the latch plate and latch against movement.

6. The combination with the latch and the latch plate in a door lock of a casing inclosing the same, a stop member formed in the 125 casing over which the latch plate is normally adapted to ride, a spindle extending through the casing, a knob on the spindle, means on the spindle for retracting the latch and 130

means on the spindle for depressing the latch plate to lock it against movement.

7. The combination with the latch and the latch plate in a door lock of a casing inclosing the same, a stop member formed in the casing over which the latch plate is normally adapted to ride, a spindle extending through the casing, a knob on the spindle, means on the spindle for retracting the latch, and 10 means actuated by the knob for depressing the latch plate to lock it and the latch against movement.

8. The combination with the latch and the latch plate in a door lock of a casing inclosing the same, a stop member formed in the casing over which the latch plate is normally adapted to ride, a yielding member adapted to normally support the latch plate in said position, a spindle extending 20 through the casing, a knob on the spindle, means on the spindle for retracting the latch and means on the spindle for depressing the latch plate to lock it against movement.

25 9. The combination with the latch and the latch plate in a door lock of a casing inclosing the same, a stop member formed in the casing over which the latch plate is normally adapted to ride, a yielding member adapted to normally support the latch plate in said position, a spindle extending through the casing, a knob on the spindle, means on the spindle for retracting the latch and means actuated by the knob for 35 depressing the latch plate to lock it and the latch against movement.

10. In a door lock the combination with a latch and latch plate slidably mounted in the casing of the lock of a spindle turnably mounted in the casing, a stop member over which the latch plate is normally adapted to slide, a yielding member adapted to support the latch plate, a hub member 40 slidably mounted on the spindle and means for moving the hub on the spindle to depress the latch plate to a position where it will engage the stop and become locked against sliding movement.

45 11. In a door lock the combination with a latch and latch plate slidably mounted in the casing of the lock of a spindle turnably mounted in the casing, a stop member over which the latch plate is normally adapted to slide, a yielding member adapted 55 to support the latch plate, a hub member slidably mounted on the spindle, a door knob secured on the spindle, and means controlled by the knob for moving the hub lengthwise on the spindle to a position

where it will engage and depress the latch plate into engagement with the stop.

12. In a door lock the combination with a latch and latch plate slidably mounted in the casing of the lock of a spindle turnably mounted in the casing, a stop member over 65 which the latch plate is normally adapted to slide, a yielding member adapted to support the latch plate, a hub member slidably mounted on the spindle, a door knob pivotally mounted on the spindle and a connecting member between the knob and the hub adapted to move the hub lengthwise upon the spindle when the knob is swung about its pivot, said sliding movement of the hub causing the latch plate to be depressed into a position where it will engage the stop and lock the latch against movement.

13. In a door lock the combination with a latch and latch plate slidably mounted in 80 the casing of the lock of a spindle turnably mounted in the casing, a stop member over which the latch plate is normally adapted to slide, a yielding member adapted to support the latch plate, a hub member slidably 85 mounted on the spindle, a door knob pivotally mounted on the spindle and a link member between the knob and the hub adapted to move the hub lengthwise upon the spindle when the knob is swung about 90 its pivot, said sliding movement of the hub causing the latch plate to be depressed into a position where it will engage the stop and lock the latch against movement.

14. The combination in a lock of the character described, of a latch, a spindle to operate the latch, and knobs on said spindle, one of said knobs being pivotally mounted on the spindle and adapted to lock the latch against retraction by means of either knob, 100 or otherwise, and to indicate by its position whether the latch is locked or unlocked.

15. The combination with the latch in a lock and the spindle whereby it is actuated, of a knob pivotally mounted on the spindle, and means operated by swinging movement of the knob about its pivot, for locking the latch against retraction in any manner, and for indicating whether the latch is locked or unlocked.

In testimony whereof I have hereunto set my hand in the presence of two subscribing witnesses.
